US00D910635S

(12) **United States Design Patent** (10) **Patent No.:** **US D910,635 S**
(45) **Date of Patent:** **** Feb. 16, 2021**

(54) **3D SCANNER**

(71) Applicant: **ARCHIDRAW, INC.**, Seoul (KR)

(72) Inventor: **Ju Sung Lee**, Seoul (KR)

(73) Assignee: **ARCHIDRAW, INC.**, Seoul (KR)

(**) Term: **15 Years**

(21) Appl. No.: **29/678,127**

(22) Filed: **Jan. 25, 2019**

(30) **Foreign Application Priority Data**

Dec. 19, 2018 (KR) 30-2018-0059968

(51) **LOC (13) Cl.** **14-02**

(52) **U.S. Cl.**

USPC **D14/420**

(57) **CLAIM**

I claim the ornamental design for a 3D scanner, as shown and described.

DESCRIPTION

FIG. 1 is a perspective view of a 3D scanner, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 5 Drawing Sheets
